UNITED STATES PATENT OFFICE

ALBERT HENLEY, OF LAWRENCE, KANSAS.

DESIGN FOR A WIRE FENCE.

SPECIFICATION forming part of Design No. 29,160, dated August 2, 1898.

Application filed June 27, 1898. Serial No. 684,625. Term of patent 14 years.

To all whom it may concern:

Be it known that I, ALBERT HENLEY, a citizen of the United States, residing at Lawrence, in the county of Douglas and State of Kansas, have invented and produced a new and original Design for Wire Fences, of which the following is a specification, reference being had to the accompanying drawing, forming part thereof, and in which the figure is a side view of a section of a fence, showing my new design.

My design consists in the series of horizontally-disposed trapezoidal figures where parallel sides are approximately vertical and are made of the same length throughout the same rows and of gradually-increasing length from row to row and whose other two sides are of the same length throughout and converge from one of the parallel sides toward the other, producing meshes of trapezoidal form of uniform length laterally throughout the fence, but increasing in width vertically from edge to edge of the fence.

In the drawing the adjacent horizontal rows

of meshes converge in opposite directions, one to the right and the other to the left, and there are formed at the juncture of the ends A and the sides B of the trapezoidal meshes the inclined twisted connecting portions C. The meshes D at the top of the fence and E at the bottom thereof partake on one side of the characteristics of the general design before described, while they are bordered on their outer sides by the twisted strand F and the twisted and barbed strand G. While the meshes are of uniform length in a horizontal direction, they vary in width vertically, being narrowest at the bottom of the fence and gradually widening toward the top.

Having described my invention, what I claim as new, and desire to secure by Letters Patent, is—

The design for a wire fence as herein shown and described.

ALBERT HENLEY.
